LIGHT CHAMBER HOUSING FOR A PHOTOGRAPHIC SLIDE PROJECTOR

Herold M. Schlegel, Ann Arbor, Mich.

Application September 11, 1951, Serial No. 16,687

Term of patent 7 years

(Cl. D61—1)

To all whom it may concern:

Be it known that I, Herold M. Schlegel, a citizen of the United States, residing at Box 381, 2812 Fernwood, Ann Arbor, in the county of Washtenaw and State of Michigan, have invented a new, original, and ornamental Design for a Light Chamber Housing for a Photographic Slide Projector, of which the following is a specification, reference being made to the accompanying drawings, forming a part thereof.

In the drawings:

Figure 1 is a top view of the light chamber housing for a photographic slide projector, showing my new design;

Figure 2 is a side view of the said housing;

Figure 3 is a rear view thereof; and

Figure 4 is a front view thereof.

I claim:

The ornamental design for a light chamber housing for a photographic slide projector, substantially as shown.

HEROLD M. SCHLEGEL.
